UNITED STATES PATENT OFFICE.

HERMAN BACKMAN, OF CHICAGO, ILLINOIS, ASSIGNOR TO VARIETY MANUFACTURING COMPANY, OF CHICAGO, ILLINOIS, A CORPORATION OF ILLINOIS.

FIRE DOOR, SAFETY GATE, AND THE LIKE.

1,415,977.

Specification of Letters Patent. Patented May 16, 1922.

Application filed June 20, 1919. Serial No. 305,569.

To all whom it may concern:

Be it known that I, HERMAN BACKMAN, a citizen of the United States, residing at Chicago, in the county of Cook and State of Illinois, have invented a certain new and useful Improvement in Fire Doors, Safety Gates, and the like, of which the following is a full, clear, concise, and exact description, reference being had to the accompanying 10 drawings, forming a part of this specification.

My invention relates to fire doors, safety gates and the like.

While my invention is particularly adapted for use in connection with that class of fire doors or safety gates which comprise a pair of vertical sliding sections, which sections meet when the door is in closed position and move vertically away from each 20 other in opening, I do not intend to limit the invention to such use or purpose only.

Doors of this general description are particularly adapted for use in elevator shafts. The prior art has generally found it necessary to so counterweight the upper section in a door of this type that upon releasing the retaining means for retaining the door in open position the greater weight of the upper section of the door will move this section 30 downwardly and the lower section upwardly through suitable connections to close the door. This presents a considerable practical difficulty in that not only the friction of the moving parts but the difference in 35 weight between the two sections must be overcome by the operator in opening the door. A further disadvantage of the prior art structures is the very severe shock or impact to which the sections are subjected 40 as they are brought together at the end of their closing movement. Such a shock or impact is not only disturbing but is injurious to the hanging of the door and the sections themselves.

45 In accordance with the teachings of my invention I have made provision whereby the sections of such a door need be only started in their opening movement, sufficient momentum being thereafter induced to move 50 the sections into full open position. In order that the sections will not end their opening movement with a severe shock, I have provided for checking or stopping the action of such momentum inducing means before

the full open position of the sections is 55 reached, the greater weight of the upper section thereafter serving to check the speed of the sections so that their movement will be ended without an impact. During the upward movement of the lower section this 60 means is again brought into action to check the momentum induced by the greater weight of the upper section so that the sections of the door will be brought together into closed position without violence. 65

In order that those skilled in the art may be fully acquainted with the nature and scope of my invention I shall describe a specific embodiment of the invention in connection with the accompanying drawings 70 which form a part of the present specification.

Figure 1 is a front elevational view of a door of the type particularly adapted for use in connection with elevator shafts showing an embodiment of my invention in connection therewith;

Figure 2 is a horizontal sectional view taken on the line 2—2 of Figure 1;

Figure 3 is a vertical sectional view taken 80 on the line 3—3 of Figure 1; and

Figure 4 is an enlarged fragmentary horizontal section.

This invention is not concerned with the details of construction of the door but I will 85 give such a description of a particular form of slide door as will enable those skilled in the art to clearly understand a particular embodiment of my invention in connection therewith. 90

The form of door shown is particularly adapted for closing the usual doorways providing communication between an elevator shaft and the various floors of the building, although it is useful in other connections. 95 The door comprises two panel members or sections 1 and 2, running in suitable vertical guiding members 3 and 4. The two panel members 1 and 2 are connected by means of rods 5 and flexible members such 100 as chains 6. The chains 6 which are secured to blocks 7 carried by the upper panel 1 travel over sheaves 8 housed in suitable brackets 9, these brackets being mounted upon the wall 10 above the doorway closed 105 by the panel members 1 and 2. The rods 5 to which the opposite ends of the chains 6 are secured are adjustably connected to

plates 11, one of which plates is secured to each of the opposite vertical edges of the lower panel 2.

The latching arrangement for the door in this particular instance comprises a disk 12 to which is secured a handle 13 whereby the disk which is pivotally mounted upon the lower panel 2 is rotated. The disk 12 has pivoted thereto arms 14 and 15, the outer ends of which arms are arranged to engage stops 16 secured to the vertical guiding members 3 and 4 respectively, as shown in Figure 1. A spring 17 maintains the handle 13 normally in the position shown and the arms 14 and 15 in their outermost or projected position. When the panels 1 and 2 are brought together the arms 14 and 15 are sprung into place over the stops 16. Opening of the door necessitates withdrawal of the arms 14 and 15 from their engagement with the stops 16, this being accomplished by rotating the disk 12 by means of the handle 13.

It is customary to so counterweight the upper section or panel in a door of this type that when it is desired to close the door the retaining means (not shown) for maintaining the door in open position is released and the upper panel being sufficiently counterweighted to overcome the weight of the lower panel moves downwardly, moving the lower panel upwardly through the rod and chain connections 5 and 6. When the door is employed in an elevator shaft, for example, the retaining means for maintaining the door in open position is preferably released automatically as the car leaves the floor. The door is opened by rotating the disk 12 sufficiently to withdraw the arms 14 and 15 from their engagement with the stop members 16, the operator then moving the lower panel 2 downwardly, whereupon the upper panel 1 will be moved upwardly as hereinbefore described. It will now be apparent that in order to move the lower panel 2 downwardly sufficient force must be exerted by the operator to overcome the weight of the upper panel 1.

In accordance with the teachings of my invention, a pair of counterweights 18 and 19 are arranged for vertical movement in guides 20 and 21 respectively, mounted upon the wall 10 adjacent the outer vertical edges of the guiding members 3 and 4 respectively. Their weight is transmitted to the lower panel 2 of the door through bolts or other suitable projecting stems 22 which engage the upper edges of the plates 11 carried by the opposite vertical edges of the lower panel 2. The threaded shanks of the bolts 22 are secured in the counterweights 18 and 19 and project forwardly therefrom through suitable vertical slots 23, provided in the front walls of the guides 20 and 21 respectively. The counterweights 18 and 19 are

provided with a series of apertures 24 aligned vertically with the slots 23 provided in the front walls of the guides 20 and 21 whereby the bolts 22 may be secured in the counterweights in any desired vertical position for a purpose which will be hereinafter made apparent. The particular contour of the guides 20 and 21 and counter weights 18 and 19 is immaterial in that the counterweights might be cylindrical and the guides tubular if so desired.

Upon releasing the latching mechanism and starting the lower panel 2 in its downward movement, the counterweights 18 and 19 serve as supplemental weights in that they assist in overcoming the greater weight of the upper section or panel 1, giving the panels sufficient momentum to move them to full open position.

I have observed that upon providing counterweights for giving the panels sufficient momentum to move them to full open position that after sufficient force has been exerted to start the panels in their opening movement that the panels frequently end their opening movement with considerable shock or impact. This is undesirable due not only to the noise or disturbance created, but such a shock is injurious to the hanging of the door and even the sections themselves. Accordingly I have provided stops 25 adjacent the lower open ends of the guides 20 and 21 respectively, for limiting or stopping the downward movement of the weights 18 and 19 before the sections 1 and 2 reach full open position. The momentum of the panels or sections induced by these weights is sufficient to thereafter move the sections into full open position while the weight of the upper panel or section 1 will, upon stopping the travel or action of the counterweights 18 and 19, check the speed of the panels so that their movement will be ended without an impact.

The proper point in the downward travel of the panel or section 2 for limiting or stopping the travel or action of the counterweights 18 and 19 is determined by the size of the panels, the size of the counterweights and such friction as might be appreciable. I have provided means whereby the point in the downward travel of the section 2 at which the action of the counterweights 18 and 19 is stopped or limited can be quickly and readily adjusted to meet various conditions. This is accomplished by removing the bolts 22 and securing these bolts in either of the other various aligned apertures 24, provided in the counterweights. The amount of downward movement of the counterweights is regulated or adjusted in this manner.

Assume that the door is in the open position indicated by dotted lines in Figure 1. Upon releasing the retaining means for

maintaining the panels or sections in this position, the greater weight of the upper section is sufficient to overcome the weight of the lower section 2, causing the upper section 5 to move downwardly and the lower section upwardly. The projecting bolts 22 are engaged by the plates 11 during this upward movement of the lower section 2, the momentum induced by the greater weight 10 of the upper section being sufficient to move the sections into closed position and the counterweights 18 and 19 into the position shown in full lines. The counterweights serve in this instance to check the momentum 15 of the panels or sections 1 and 2 induced by the greater weight of the section 1, checking the speed of the sections so that the door will close without violence. Violent closing of such a door is not only disturbing and injurious 20 to the door, but is dangerous to the operator.

The feature of cushioning the movement of the door to prevent its ending its closing or opening movement with a severe shock 25 together with the feature of providing whereby the door need be only started in its opening movement and sufficient momentum will thereafter be induced to move the door into full open position, all of said means 30 being adjustable to meet various conditions, are highly important aspects of my invention.

While I have described my invention in connection with the details of a particular 35 embodiment, I do not intend thereby to limit the invention to such details as I am aware and contemplate that modifications and changes may be made without departing from the invention which is set out in the 40 appended claims.

I claim:

1. In combination, a closure comprising

upper and lower sections movable vertically away from each other, counterweight means 45 tending to move said vertically movable sections toward one another, counterweight means adapted to oppose the action of said first counterweight means and means adjustably carried by said second counterweight means for bringing said means into 50 action to oppose the action of said first counterweight means, the adjustability of the means for bringing said second counterweight means into action providing adjustability of the point at which the checking 55 force of said means is brought into action whereby the speed at which the door sections are brought together may be varied.

2. In combination, a vertically movable closure member, a relatively stationary guide 60 member arranged to one side of the closure member, counterweight means arranged for vertical movement in said guide member, said counterweight means having a series of vertically arranged stud receiving apertures, 65 relatively fixed stop means for said counterweight means, a projecting stud adapted for cooperation with either of said stud receiving apertures whereby vertical adjustment of the stud may be had, means carried by the 70 closure member for cooperation with said projecting stud to effect movement of the closure member and the counterweight means in unison, the adjustability of the stud carried by said counterweight means providing 75 adjustability of the position, in the vertical movement of the closure member at which engagement and disengagement with the projecting stud is had whereby the speed of the closure member at the limit of its movement may be varied.

In witness whereof I hereunto subscribe my name this 17th day of June, 1919.

HERMAN BACKMAN.
